UNITED STATES PATENT OFFICE.

BURR M. BACKUS, OF LOS ANGELES, CALIFORNIA.

INDIVIDUAL-ACCOUNT FILE.

No. 921,340.

Specification of Letters Patent.

Patented May 11, 1909.

Application filed June 30, 1908. Serial No. 441,246.

To all whom it may concern:

Be it known that I, BURR M. BACKUS, a citizen of the United States, residing at Los Angeles, in the county of Los Angeles and State of California, have invented a new and useful Individual-Account File, of which the following is a specification.

One object of this invention is to provide convenient means for filing individual accounts in such manner that the accountant can tell at a glance, by examining the file when stored away in a pigeon-hole or other file-case, the state of the account of the person to whom the file is devoted.

Other objects are cheapness, simplicity and convenience.

The invention embraces a file comprising two hinge members, one of which is provided with a tab arranged to extend across the end of the other member to serve as a name-plate, and to bend an account-slip across the end of the account-slip when the file is placed in a pigeon-hole.

The accompanying drawings illustrate the invention in the form I at present deem most desirable.

Figure 1 is a perspective view of the file closed and in use. Fig. 2 is a perspective view of the file open. Fig. 3 is a section on line indicated at x^3 , Fig. 1. Fig. 4 is a section on line indicated at x^4 , Fig. 1. Fig. 5 is a fragmental view of a file-case for use in carrying out this invention, one of the files being shown in its pigeon-hole.

1 is a body or support adapted to hold account-slips 2. 3 is a cover in the form of a clip hinged at 4 to the body 1 and provided with a renitent tab 5 adapted to extend across one end of the body 1 when the clip 3 is folded onto the body; the purpose of the tab being three-fold; namely,—first, to fold the end of the account-slip across the end of the support 1 therefor, thus to bring into view the footing 6 of said account-slip; second, to afford a name-plate upon which can be placed the name 7 of the individual to whom the file is devoted; and third, to afford friction to hold the file closed during ordinary handling of the same.

The body 1 and the clip 3 may be made of any suitable material, as cheap metal bent into form adapted for the purpose stated,

the two parts being provided with hinge eyes 8, 9, secured together by a pintle 10. 55

11 is a supplementary clip pivoted on the pintle 10 and actuated by a spring 12 to hold the account-slips 2 in place when the cover 3 is open. Said clip 11 is accessible through an orifice 13 formed in the cover 3, 60 and is provided with a thumb-piece 14 projecting beyond the pintle 10 so that when the thumb-piece is pressed toward the body 1 the free edge of the clip 11 will be lifted to release the account-slips 2. Said free end 65 is provided with lateral extensions 15 beneath the cover 3 so that when the cover is closed the same may be raised simultaneously with the clip 11 by the pressure of the thumb upon the thumb-piece 14. When the clip 70 11 has been released the cover 3 may be returned to its closed position.

16 designates a pigeon-hole-case adapted for use with the file hereinbefore described. The same is provided with pigeon-holes 17 75 appropriate to receive the individual files. The pigeon-holes and the files may each be numbered as indicated at 18 and 19, so that each file may be placed in its appropriate pigeon-hole without confusion. 80

The cover 3 is preferably made of material of such resiliency that when the slips are engaged by the tab the same will yield to accommodate a greater or less number of slips, and to fold over the end of either one 85 or more slips as occasion may require. The same also affords sufficient friction to hold the cover normally closed but adapted to be readily thrown up by the operation of the clip when the thumb is applied to the thumb-piece for opening the file. 90

The invention is not limited to the specific details, and may be variously embodied.

In practical use, the accountant will indorse upon the tab 5 the name of the individual with which the account is kept, and will then apply the appropriate account to an account slip 2, and footing this at the bottom of the account-slip, will then place said slip in the file, allowing the portion 100 thereof which contains the footing to project beyond the end of the body 1. He will then let the clip 11 close upon the same to hold it in place, and will then close the cover 3 on said slip, thus allowing the tab 5 to 105 bend down the overhanging or extending

portion or the slip which contains the footing, so that the same can be seen by looking at the end of the file and in connection with the name of the individual to whom the account belongs. The file may then be put into a pigeon-hole alone or with other files of the same character.

I claim:—

1. A file comprising two members hinged together, one of said members being provided with a tab to extend across the end of the other member to bend an account-slip to exhibit the footing of said slip when the file is viewed from the end.
2. A file provided with a name-plate adapted to fold the end of an account-slip at the end of the file to bring the footing of the account-slip into view in connection with the name on the name-plate.
3. A file comprising a body, a cover hinged to said body and provided with a resilient tab to extend across the end of the body when the cover is closed.
4. A file comprising a body, a cover hinged to the body and provided with a tab to ex-

tend across the end of the body, and a supplementary clip to hold account-slips on the body when the cover is raised.

5. A file comprising a body, a cover hinged to the body, and a supplementary clip accessible when the cover is closed and adapted to lift the cover when the clip is lifted.

6. A sheet metal body bent at one edge to form a portion of a hinge; a cover bent to form another portion of the hinge and provided with a tab to extend across the end of the body, and a pintle to connect the hinge portions of said body and cover.

7. A file comprising a body, a cover hinged to the body and provided with a resilient tab to fold an account-slip or slips across the end of the body.

In testimony whereof, I have hereunto set my hand at Los Angeles, California, this 24th day of June, 1908.

BURR M. BACKUS

In presence of—

JAMES R. TOWNSEND,
M. BEULAH TOWNSEND.
